H. A. DAVIS

CLOTHES WASHER

Filed April 2, 1925

Patented July 20, 1926.

1,593,390

UNITED STATES PATENT OFFICE.

HERBERT A. DAVIS, OF LA GRANGE, ILLINOIS.

CLOTHES WASHER.

Application filed April 2, 1925. Serial No. 20,056.

This invention relates to an improved clothes washing accessory adapted to be removably placed within an ordinary copper or galvanized wash boiler for the purpose 5 of assisting in the proper boiling of soiled clothes.

It is an object of this invention to provide an ordinary wash boiler with an auxiliary device adapted to be placed within the 10 boiler upon the bottom thereof, said device having the base thereof arranged with a transverse partition and with side recesses to materially increase the efficiency of the auxiliary device so that clothes within the 15 boiler may be thoroughly boiled.

It is also an object of this invention to provide an auxiliary device for a wash boiler, said device having a base of improved construction to cause a sheet of water to circulate through the boiler under and around 20 said base to cause the auxiliary device to wash or boil clothes more efficiently.

It is a further object of this invention to provide an ordinary clothes boiler with an 25 auxiliary boiler device wherein a heavy base member has apertured upright pipes connected thereto and has the interior of the base divided by means of a transverse partition to cause a forced circulation through 30 each of the upright pipes independently of the other to facilitate boiling of clothes within the boiler.

It is an important object of this invention to provide an improved auxiliary boiler device 35 for use in an ordinary wash boiler, said device being of simple and improved construction with the base thereof designed to not only improve the circulation of the hot water within the boiler by means of an increased circulation of the water in the 40 form of a sheet through elongated recesses in the sides of the base, but also having partition means within the base whereby each of a plurality of steam spray pipes may be 45 independently supplied with steam pressure generated in the respective base chambers of the device.

Other and further important objects of 50 this invention will be apparent from the disclosures in the specification and the accompanying drawings.

This invention (in a preferred form) is illustrated in the drawings and hereinafter more fully described.

On the drawings:

Figure 1 is a side elevation of an ordinary

clothes boiler having one of the side walls thereof broken away to illustrate the improved clothes washer device embodying the principles of this invention.

Figure 2 is a bottom plan view of the clothes washer removed from the boiler.

Figure 3 is an enlarged longitudinal section taken on line III—III of Figure 2.

Figure 4 is a transverse section taken on line IV—IV of Figure 3.

As shown on the drawings:

The reference numeral 1 indicates an ordinary copper or galvanized tin wash boiler with the cover removed. The boiler is 70 adapted to have removably placed therein a clothes washer device embodying the principles of this invention and comprising a heavy iron hollow base embracing the top plate 2 and a downwardly directed peripheral flange 3. The base plate has straight sides while the ends thereof are rounded or semi-circular as clearly illustrated in Figure 2. Each of the side flange walls of the base has the lower margin thereof cut away to afford an elongated longitudinal recess or opening 4 leaving the end portions of the base flange in the form of legs which are adapted to rest upon the inner face of the bottom of the boiler as illustrated in Figure 80 1. The base is provided with a middle transverse partition or wall 5 the bottom edge of which terminates in the plane of the edges of the recesses 4. The transverse partition 5 divides the interior of the base into a pair 90 of chambers 6. Integrally formed on the top of the base section are a plurality of upwardly directed sleeves or collars 7 which are internally threaded to removably receive the lower threaded ends of a plurality 95 of upright spray pipes or nozzles 8 each of which is provided with a plurality of rows of spray apertures 9. Rigidly secured on the top of each of the spray pipes 8 is a cap 10.

The operation is as follows:

The improved clothes washer of this invention is adapted to be placed within an ordinary clothes boiler with the heavy base thereof resting or standing upon the inner 105 face of the bottom plate of the boiler. The base section is made heavy and may be constructed of cast metal such as iron having a copper coating. The base section is purposely made heavy so that the improved device will remain firmly seated in position within the boiler and furthermore be of 110

sufficient strength to rigidly support the apertured stand-pipes.

After the improved clothes washer has been placed in position within the boiler 1 5 the boiler is filled with water and soiled clothes with the level of the water below the level of the closure caps 10 of the pipes 8 (Figure 1). The boiler with its lid in position may now be placed on an ordinary 10 stove or a gas stove as the case may be, to permit the water within the boiler to be heated to a boiling temperature by the heat from the stove. When the water is boiling within the boiler, circulation is, of course, 15 set up so that the clothes will be boiled to facilitate washing of the same.

By using the improved clothes washer of this invention in an ordinary type of wash boiler the circulation of water and steam 20 is materially increased. This is brought about by the improved construction of the base of the device which as clearly illustrated in Figure 3 is provided with the side elongated recesses 4. These recesses are dis- 25 posed opposite to one another and permit a sheet of hot water to pass through the sides of the base and upwardly over the top thereof in substantially the form of a sheet or ribbon of boiling water so that an increased 30 circulation of boiling water is obtained within the boiler to thoroughly agitate the clothes to loosen or boil out the dirt contained therein. In addition to the im- 35 proved circulation of the water by means of the side recesses in the base of the device the transverse partition 5 in the base di- 40 vides said base into a plurality of chambers so that a steam pressure is generated in each of said chambers with a pressure head suffi- 45 cient to permit a forced upward circulation of steam through each of the apertured steam spray pipes 8 independently of one another. The steam under pressure pass- 50 ing upwardly through the respective pipes 8 is forced out of the apertures 9 in all di- 55 rections and into the clothes within the boiler so that the clothes are quickly and thoroughly boiled.

The base is made heavy for the purpose of 55 forming a stable device which will not be readily moved and which will be of a

weight sufficient to offset the pressure of the steam generated in the chambers of said base so that the pressure of the steam in the spray pipes 8 will not upset or move the de- 65 vice within the boiler.

The improved clothes washer device of this invention with the partition and the heavy base for holding the apertured spray pipes, is an advance in the washing art and affords a means whereby boiling of clothes is greatly improved so that clothes may be thoroughly boiled within a very short time within an ordinary clothes boiler so that steam under pressure is forced outwardly 65 through the spray pipes through the clothes and through the boiling water within said boiler. The chambered arrangement of the base permits each of the spray pipes 8 to be independently provided with steam pressure 70 from its respective base chamber, while the elongated side recesses in the base greatly increase the circulation of water and steam within the boiler and through the clothes.

I am aware that many changes may be 75 made and numerous details of construction may be varied through a wide range with- 80 out departing from the principle of this in- vention, and I therefore do not purpose 85 limiting the patent granted hereon, other- 90 wise than necessitated by the prior art.

I claim as my invention:

The combination with a clothes boiler, 85 of a clothes washer device disposed therein, comprising a heavy base plate, a downward- 90 ly directed flange integrally formed on the periphery of said base plate to afford a stand for the base plate, said flange having the side walls thereof cut away to afford a 95 pair of oppositely disposed longitudinal re- cesses, a transverse partition integrally formed within said base dividing the in- 100 terior thereof into a plurality of chambers, the lower edge of said partition terminating in the plane of the edges of the cut away portions of the base side walls, and aper- tured spray pipes projecting vertically from said base plate and communicating with said chambers therein.

In testimony whereof I have hereunto sub- 100 scribed my name.

HERBERT A. DAVIS.
